UNITED STATES PATENT OFFICE.

GEORGE E. MARLATT, OF PASADENA, CALIFORNIA.

TYPOGRAPHICAL MACHINE.

1,263,266.

Specification of Letters Patent. Patented Apr. 16, 1918.

Application filed January 23, 1917. Serial No. 144,091.

To all whom it may concern:

Be it known that I, GEORGE E. MARLATT, a citizen of the United States, residing at Pasadena, in the county of Los Angeles and 5 State of California, have invented new and useful Improvements in Typographical Machines, of which the following is a specification.

My invention relates to typographical 10 machines of the linotype class and the primary object thereof is to provide certain automatic safety devices which may be controlled by and serve to control the opening of the vise frame.

15 It is a well known fact to operators of such machines, that it is unsafe to open the vise frame at certain stages of operation of the machine, while at other stages of operation, between and during the successive normal relations of the operating parts, the vise may be safely opened.

When the machine operating parts are in certain relative positions, if the vise is opened there is danger that the metal pump 25 will operate and thus cause an uncontrolled flow of metal from the pot. At other relative positions of these parts there is danger of breakage or damage to certain of the parts, as for instance, to the vise closing connecting rod.

As stated, the vise may be safely opened 35 at times, as for instance, when the first and second justification levers are in their normal or lowermost positions, and in this invention advantage is taken of this fact or condition for preventing the opening of the vise at other times, and also for causing the justification levers to serve as counterbalances for the weight of the vise when the 40 same is being opened.

Referring to the drawings, in which similar characters of reference indicate the same parts throughout the specification and the several views of the drawing, Figure 1 45 is a side elevation of the lower portion of a machine with my improvements shown thereon; Fig. 2 is a plan of the same, and Fig. 3 is an enlarged view of the starting and stopping means.

50 In the drawings, 1 is the vise frame, 3 the pump for forcing the metal from the pot to the mold, 4 the metal pot and 5 is the vise closing connecting rod. The first justification lever 6 carries a roller 8 which is held 55 against and follows the irregular periphery of a cam 10 by means of a spring 9, for

causing the pivotal movement of the lever on its fulcrum pin 11 for the purpose of justifying the line of matrices and space-bands, in the ordinary manner.

60 The second justification lever 7 carries a similar roller 12, which is spring actuated and operates in contact with a cam 13, this roller and the lever 7 being similar in function and operation to the lever 6 and its 65 roller.

In order to carry out the objects of my 70 invention, I provide the first justification lever 6 with a lug 14, and the vise frame 1 is provided with an arm 15 which carries 75 an extended pin 16. When the lever 6 occupies a position above its normal position, as shown in Fig. 1, the pin 16 on the arm 15 of the frame 1 engages the rear edge of the vertically extended lug 14 and prevents 80 the opening of the vise, as will be readily apparent. When the vise is opened, the pin 16 will engage the inclined upper edge of the lug 14, thus forcing the lever 6 downwardly to a point slightly below its normal 85 position and against the tension of a spring 9 which is common to all machines of this class, and the lever thus serves as a support for the weight of the vise as it is lowered pivotally about its fulcrum pin 17. 85

The second justification lever 7 has a lug 18 which is adapted to be engaged by a pin 19 carried by an arm 20 on the vise, and the function and operation of these elements are similar to those described in connection with the lever 6.

In the operation of machines of this class, it is necessary to close the starting and stopping handle 21 before the vise is opened, as otherwise, there would be danger resulting 95 from the operation of the machine parts during the time the vise is lowered. Heretofore it has been necessary to manually close the handle 21 before the opening of the vise, but in this invention I provide 100 means for automatically closing the same, and for this purpose a lug 22 is provided on the vise frame 1 and an extension 23 is formed on the handle 21, so that when the vise is opened, the lug 22 will engage the 105 extension 23 and force the handle 21 inwardly for a sufficient distance to effect the movement of a connecting link 24 which is attached to the handle 21 at one end and to the starting and stopping rod 25 at the 110 other end, across its dead center and over the center of the rod 25, by means of a clutch

spring 26. When the handle 21 is thus moved over its dead center, it is further moved by the action of the spring 26 and a clearance is thus provided between the lug 5 22 and the handle extension 23, so that when the vise is raised to normal position the lug 22 will not engage the extension 23, and necessitate the manual withdrawal of the handle 21 before the machine is again 10 operative.

Having thus described my invention, what I claim is:

1. A typographical machine including the vise frame, the justification levers, and 15 means for operably connecting said vise frame and said levers and means for locking said vise frame against movement at improper times.

2. A typographical machine including the 20 vise frame movable to and from operating position, the justification levers for expanding the line of matrices carried by said vise frame, and co-acting means on said frame and said levers for locking said frame 25 against movement at improper times.

3. A typographical machine including the vise frame movable to and from operating 30 position, the justification levers for expanding the line of matrices carried by said vise frame, and means operable by said justification levers for locking said vise frame against operation at improper times.

4. A typographical machine including the 35 movable vise frame, the first and second justification levers for expanding the line of matrices carried by said vise frame, and means on each of said levers co-acting with separate means on said vise frame for locking said frame against movement at 40 improper times.

5. A typographical machine including the 45 movable vise frame, the justification levers for expanding the line of matrices, the justification springs for maintaining said levers in operating position, and means for utilizing said springs for counterbalancing the weight of said vise frame when the same is moved out of operating position.

6. A typographical machine including the 50 movable vise frame, the justification levers

for expanding the line of matrices, the justification cams for operating said levers, the springs for maintaining the engagement between said cams and said levers, means for locking said vise frame against movement 55 at improper times, and means for utilizing said springs for counterbalancing said vise frame when the same is moved out of operating position.

7. A typographical machine including the 60 movable vise frame, the starting and stopping lever for regulating the operation of the machine, and means whereby the opening of the vise frame will force said starting and stopping lever from normal position and into safety position.

8. A typographical machine including the 65 movable vise frame, the starting and stopping lever for regulating the operation of the machine, and means on said vise frame 70 for operating said lever to an extreme position of safety when said vise frame is opened.

9. A typographical machine including the 75 movable vise frame, starting and stopping means for regulating the operation of the machine, justification means, and means associated therewith for preventing the opening of the vise frame at improper times.

10. A typographical machine including 80 the movable vise frame, the starting and stopping lever for regulating the operation of the machine, means on said vise frame for operating said lever, the justification levers for expanding the line of matrices, 85 means on said vise frame and said levers for preventing the opening of said frame at improper times, the justification springs for maintaining said levers in operating position, and means for utilizing said springs 90 for counterbalancing said vise frame when the same is opened.

Signed at Los Angeles, in the county of Los Angeles, and State of California, this 17th day of January, 1917.

GEORGE E. MARLATT.
